(57) **CLAIM**

The ornamental design for a thermal immersion circulator, as shown and described.

DESCRIPTION

FIG. 1 is a top left-front isometric view of a thermal immersion circulator showing our new design.

FIG. 2 is a top right-rear isometric view thereof.

FIG. 3 is a front elevational view thereof.

FIG. 4 is a left side elevational view thereof.

FIG. 5 is a right side elevational view thereof.

FIG. 6 is a rear elevational view thereof.

FIG. 7 is a top plan view thereof; and,

FIG. 8 is a bottom plan view thereof.

The broken lines are included for the purpose of illustrating portions of the thermal immersion circulator that form no part of the claimed design.
